CARL R. GESE, OF JERSEY CITY HEIGHTS, NEW JERSEY

RAILWAY-RAIL JOINT

Application filed May 29, 1929. Serial No. 366,962.

This invention relates, generally, to railway-rail construction, and the invention has reference, more particularly, to means for connecting or tying adjoining railway rails, 5 such tying means being commonly known as rail joints.

The principal object of the invention is to provide a novel railway-rail joint consisting of a unitary member or tie-plate that may be 10 readily and quickly assembled with adjoining railway-rails to tie the same together without the necessity or use of bolts or other additional fastening means.

Another object of the invention lies in the 15 provision of a rail joint of the above character which is of simple construction and reliable in operation and which cannot become loose or ineffective in use or rendered inoperative by unauthorized persons.

20 The common railway-rail joint employing fish-plates bolted to the sides of the rail webs are objectionable inasmuch as the vibration and jarring of the rails in use owing to the passage of traffic results in a constant loosening of the fish-plates resulting at times in 25 the failure of the joint or spreading of the rails.

The present invention employs unitary tie-plates for connecting adjoining rails, which 30 tie-plates are received within recesses in the rails and are forced to desired locked position with the rails not only by the spiking of the rails to the ties, but also by the weight of the passing traffic.

35 Other objects of the invention not at this time more particularly enumerated, will be clearly understood from the following detailed description of the same.

The invention is clearly illustrated in the 40 accompanying drawings, in which:—

Fig. 1 is a perspective view of a section of a railway-track embodying the principles of the present invention and illustrates a manner of assembling adjoining rails;

45 Fig. 2 is a view similar to Fig. 1 but illustrates the adjoining rails in assembled relation;

Fig. 3 is a plan view of the structure of Fig. 2 and illustrates the use of lag screws 50 for securing the rails to the ties;

Fig. 4 is a sectional view taken along line 4—4 of Fig. 3; and

Fig. 5 is a sectional view taken along line 5—5 of Fig. 3.

Similar characters of reference are employed in all of the hereinabove described views to indicate corresponding parts.

Referring now to the said drawings, the reference numerals 6 and 7 represent the abutting ends of two adjoining rails of a railway 60 track embodying the principles of the present invention. These rails are of identical construction and each is formed with a head 8, a web 9 and a spike flange 10 that is adapted to be secured to the ties 11 as by spikes 65 or preferably by lag screws 12 (see Fig. 3).

The webs 9 of the rails are thickened at the end portions 13 of the rails and these end portions are provided with central, longitudinally extending channels or recesses 14. The 70 channels 14 are of rectangular cross-section and when two adjoining rails are assembled, the adjoining channels of these rails are in alignment and are adapted to receive a rectangular tie-plate 15. Tie-plate 15 conforms in cross section to the form and dimensions of the channels 14 and when inserted in these channels at the abutting ends of two rails, it performs the function of the exterior fish-plates and bolts commonly employed. 80

Tie-plate 15 is provided at its bottom near each of its ends with oppositely extending projections or locking lugs 16 and 17 of preferably rectangular cross-section. Locking lugs 16 and 17 are adapted to be positioned 85 within slots 18 provided in the lower part of the end portions of the rails 6 and 7. Slots 18 conform in cross-section to lugs 16 and 17 and snugly receive these lugs to thereby lock the rails 6 and 7 to the tie-plate 15 and 90 hence lock these rails through the agency of the tie-plate to one another.

In assembling adjoining rails it is merely necessary to insert the tie-plate 15 into the aligned channels 14 as illustrated in Fig. 1 95 so that the locking lugs or projections 16 and 17 pass into the recesses 18 thereby locking the rails to the tie-plate and through the tie-plate to one another. The rails may be as readily disassembled by raising the rails off 100

of the ties 11 so as to permit the removal of tie-plate 15.

It will be noted that the lag screws 12 by holding the rails upon the ties 11 act to positively retain the tie-plates and their locking lugs within their respective recesses in the rails, to thereby permanently and positively tie adjoining rails together into an unitary whole. It will be noted also that the weight 10 and jarring action of passing trains tends to force the tie-plate and its locking lugs further into their respective recesses in the rails, thereby even further enhancing the efficiency of the joint.

15 Owing to the positioning of the tie-plate within the recesses 14 and 18 these plates are protected against the weather and against unauthorized disconnection from the rails.

It is apparent that the novel railway joint 20 of this invention is of extremely simple construction and may be made cheaply in large quantities.

As many changes could be made in the above construction and many apparently 25 widely different embodiments of this invention could be made without departing from the scope thereof, it is intended that all matter contained in the above description or shown in the accompanying drawings shall 30 be interpreted as illustrative and not in a limiting sense.

What is claimed is:—

1. In a railway rail joint, the combination 35 with the abutting end portions of two adjoining rails channeled longitudinally and provided at their lower portions with recesses extending transversely through the rail webs and spike flanges, of a plate member formed to fit said channels and transversely extending 40 lugs formed on said plate member and extending within said recesses through the rail webs and spike flanges to thereby lock said rails to said plate member.

2. In a railway rail joint, the combination 45 with the abutting end portions of two adjoining rails channeled longitudinally, each of said end portions having a transverse recess extending upwardly from its under surface and through the rail web and spike flange, of 50 a tie-plate formed to fit in said channels and having projections near its ends fitting into said transverse recesses for locking said rails together.

In testimony, that I claim the invention set 55 forth above I have hereunto set my hand this 25th day of May, 1929.

CARL R. GESE.
